UNITED STATES PATENT OFFICE.

AXEL C. V. MALM AND LEOPOLD RAUH, OF DAYTON, OHIO, ASSIGNEES TO THE EGEY REGISTER COMPANY, OF DAYTON, OHIO, A CORPORATION OF OHIO.

MANIFOLDING ATTACHMENT FOR TYPE-WRITERS.

1,144,147.

Specification of Letters Patent. Patented June 22, 1915.

Application filed October 24, 1914. Serial No. 868,372.

To all whom it may concern:

Be it known that we, AXEL C. V. MALM and LEOPOLD RAUH, citizens of the United States, residing at Dayton, in the county of 5 Montgomery and State of Ohio, have invented certain new and useful Improvements in Manifolding Attachments for Type-Writers, of which the following is a specification, reference being had therein to 10 the accompanying drawing.

This invention relates to manifolding attachments for typewriters, of that type in which one or more webs of paper are fed from rolls, supported in the rear of the typewriter, through a series of ribbons supported by special ribbon-carrying devices and interposed between the usual typewriter ribbon and the platen.

The object of the present invention is to 20 provide a ribbon carrying frame, to support a manifolding ribbon in proper relation to the platen of the typewriter carriage, which can be readily applied to a typewriter carriage without modification of the latter.

25 A further object is to so construct this supporting frame that it can be quickly and easily connected with the typewriter carriage without the use of tools or skill on the part of the operator, and to this end it is 30 also an object of the invention to so construct the frame that it will slip onto a fixed part of the typewriter carriage and will be movably supported thereby, to permit the ribbons to be moved into and out of their 35 operative positions; and to provide the frame with means for locking the same against movement relatively to the typewriter carriage when the ribbon is in operative relation to the platen.

40 It is also an object of the invention to provide this supporting frame with ribbon feeding devices which will be of such a character and so arranged that when the frame is in a position to support the ribbon in operative relation to the platen, the ribbon feeding devices will be arranged in operative relation to an operable part of the typewriter carriage, preferably the line spacing mechanism. And a further object is to provide 45 a mechanism of this kind which will be very simple in its construction and operation, and of a very light construction, thus

adding little to the weight of the typewriter carriage and making no appreciable difference in the operation thereof.

55

In the accompanying drawings Figure 1 is a plan view of a typewriter showing the complete manifolding attachment connected therewith; Fig. 2 is an end elevation of the attachment showing the same in place; Fig. 60 3 is a transverse, sectional view taken just inside one of the end plates of the attachment; Fig. 4 is an elevation of that end of the attachment opposite the end shown in Fig. 2; and Fig. 5 is a detail view of one 65 of the ribbon guides with the ribbon applied thereto.

In these drawings we have illustrated one embodiment of our invention and have shown the same designed for attachment to 70 the No. 10 Remington typewriter, but it will be understood that the device can, by obvious modifications, be adapted for use in connection with various other typewriters.

In these drawings we have indicated the 75 typewriter as a whole by the reference numeral 1. Mounted upon the typewriter is the usual typewriter carriage 2 in which is journaled a platen 3. Suitable line spacing mechanism is connected with the platen to 80 feed the paper forward line by line as the writing progresses, and this mechanism, as embodied in this particular type of machine, comprises a lever 4 operatively connected by means of a crank arm 5 and a connecting 85 rod 6 with a pawl 7 which is capable of bodily movement and is preferably carried by a stud 8 mounted on a rock arm 9. This pawl is adapted to engage a ratchet wheel 10 secured to the end of the platen and to rotate 90 the platen to advance the paper when the lever 4 is actuated.

The usual typewriter ribbon is indicated at 11 and is supported and operated as usual.

The whole mechanism so far described is 95 a part of the standard Remington typewriter, and no change whatever is made in this typewriter when the invention is applied thereto.

Mounted in the rear of the typewriter is 100 a paper carrier consisting of a frame 12 mounted to travel along tracks 13, carried by a base 14, and connected with the typewriter carriage by means of a connecting

rod 15 so as to cause the frame 12 to move with the paper carriage.

Mounted on the frame 12 are a plurality of rolls of paper 16. The paper from the several rolls is carried across the paper carriage of the typewriter where it is interleaved between special ribbons which are interposed between the typewriter ribbon 11 and the platen 3.

10 The paper carrier and the means of connecting the same with the typewriter carriage do not form a part of the present invention, but are fully illustrated and described in an application for patent filed 15 by Messrs. Malm, Rauh and Aker, July 20th, 1914, Ser. No. 852,024.

The special or supplemental ribbons are carried by a supporting frame which is readily attached to and removed from the typewriter carriage 2. This frame, as here shown, comprises end members 17 connected one to the other by suitable tie rods 18 and having at their forward edges suitable ribbon guides. In the present instance, the forward edges of the frame members 17 are connected by a flat bar 19 which serves as a paper support and guide, and the ribbon guides are in the form of angle plates 20 secured to the bar 19 at points near the opposite ends thereof and extending downward so that when the supporting frame is in its operative position on the carriage these ribbon guides will be located in a plane just in front of the platen. In this position the ribbon as shown at 21, which extends over and between the ribbon guides will extend for substantially the full length of the platen and will lie between the platen and the typewriter ribbon 11. These guide plates may be of any suitable character and their specific construction does not form a part of the present invention. Those here shown are so constructed that they will support the ribbon in three folds or plies, arranged one in front of the other so as to provide three copies of the matter written, in addition to the copy produced by the typewriter ribbon. The ribbon is carried by two reels or spools 22 mounted on opposite ends of a shaft 23, journaled in the end members 17 of the supporting frame. The ribbon is fed lengthwise over the guides by winding it from one reel to the other. This reeling of the ribbon may be accomplished in various ways. In the present instance the reels are loosely mounted on the shaft 23 and are provided with clutch devices for separately connecting them therewith. As here shown, these clutch devices comprise pins 24 mounted in sleeves or elongated bearings 25 secured to the shaft 23, and adapted to enter recesses or holes in the adjacent faces of the respective reels, thereby connecting the reels to the shaft.

85 In the normal operation of the device one

reel is clutched to the shaft so as to rotate therewith and wind the ribbon onto the same, while the other reel is loose on the shaft to permit it to rotate in the opposite direction and allow the ribbon to be unwound therefrom. To permit of this action, the bearings 25 are slotted as shown at 26 and the pins 24 are provided with projections or small pins 27 adapted to enter the slots 26 when the pins are in their operative positions, and to engage the ends of the bearing sleeves to hold the pins in their inoperative positions. The shaft 23 may be rotated to feed the paper in any suitable manner, but this is preferably accomplished by establishing an operative connection between the shaft and the line spacing mechanism of the carriage.

As here shown, the end of the shaft is provided with a ratchet wheel 28 which is rigidly secured thereto, and an arm 29 is journaled on the end of the shaft adjacent to the ratchet wheel and carries a pawl 30 which is adapted to engage the teeth of the ratchet and rotate the shaft when the arm 29 is rocked about its axis. This arm 29 is connected, preferably by means of a link 31, with a lever 32, which is pivotally mounted on the frame member and has one end arranged in the path of and adapted to be operated by a part of the line spacing mechanism. As here shown, this arm extends into the path of the stud 8 which carries the pawl 7 for actuating the platen, and, upon each movement of the pawl 7 the lever 32 will be operated to actuate the shaft 23. This arrangement of the ribbon feeding devices enables an operative connection to be established between the same and the line spacing mechanism by merely placing the supporting frame in position upon the typewriter carriage. There is no positive connection between the two mechanisms, but their arrangement is such that the operation of the one causes the operation of the other.

40 A spring 33 is connected with the lever 32 to retract the pawl 29 after each operation thereof. It is also desirable to provide the shaft 23 with a handle, as shown at 34, by means of which the ribbon reels may be actuated, as this materially facilitates the winding of a new ribbon on the spools and the threading of the same through the guides.

45 As has been stated, the frame is of such a character that it can be placed in position on the typewriter frame and clamped thereto without the use of tools or the exercise of skill on the part of the operator. Preferably, the end members 17 are so constructed that they will slip over or engage a part of the typewriter carriage and will thus support the frame thereon. In the present instance, the frame members 17 are provided

in the lower portions of their rear edges with inclined slots 35 which are adapted to extend over a part of the typewriter carriage and to pivotally support the frame 5 thereon. In the present instance, the typewriter carriage is provided with a rod 36, which is normally employed to support the paper shield and name plate, and this rod has been utilized as a support for the frame. 10 It is usually flat at its ends, and, in the present instance, the slots 35 are formed of a width at their ends which will enable them to slip over these flat portions of the rod, and are enlarged at their inner ends to permit the frame members to turn about the axis of the rod when they have been placed thereon. This construction, however, is not an essential one, although it is preferable that the slots should be arranged at an 15 inclination to the horizontal so that when the supporting frame is in its normal position they will hold the rear portion of the frame against vertical movement. After the slotted frame members have been placed in 20 engagement with the rod on the typewriter carriage the frame is moved downward to its normal position, in which it supports the ribbon in front of the platen, and is secured to the typewriter carriage in such a 25 manner as to hold it against movement relatively thereto. Preferably, this means is finger-actuated so that no tools will be required in connecting the attachment, and, it is here shown as comprising a finger-operated catch 37 pivoted to one of the frame members 17 and adapted to engage the shaft of the platen on the typewriter carriage. The construction of the catch and its position with relation to the shaft is such that 30 when moved into engagement with the shaft it will clamp the frame firmly to the carriage. It will be noted that this arrangement is such that pivotal movement may be imparted to the frame, without detaching 35 the same from the carriage, to elevate the ribbon guides and ribbon and place the same in a position where they will be readily accessible either to thread the ribbon through the guides or to thread the paper through 40 the ribbons. 50

The operation of the device will be readily understood from the foregoing description thereof, and it will be noted that to attach the device to the typewriter it is only necessary to place the slotted frame members in engagement with the rod on the typewriter carriage, move the frame forward to its normal or horizontal position and manipulate the finger catch 34 to clamp the frame 55 in this position.

The device is exceedingly simple, comprising very few parts, and these parts are of a simple character. Further, the parts are of such a character that they are very light of 60 weight and add little to the weight of the

typewriter carriage, and, consequently, make no appreciable difference in the operation thereof. Further, the ribbon feeding device requires no attention whatever, but is automatically placed in operative relation to the 70 line spacing mechanism when the supporting frame is placed in position on the typewriter.

It will be understood that the attachment is used in connection with a paper roll support which either before or after the attachment is secured to the typewriter carriage, is placed in position in the rear of the machine and the webs of paper from the rolls on said support are carried over the 75 carriage and supporting frame and are threaded through the supplemental ribbon as hereinbefore described.

The paper and the paper carrier are supported independently of the typewriter 80 frame and carriage so as to impose no strain thereon.

While we have shown and described one embodiment of our invention, we wish it to be understood that we do not desire to be 90 limited to the details of construction shown and described, for obvious modifications will occur to a person skilled in the art.

Having thus fully described our invention, what we claim as new and desire to protect 95 by Letters Patent, is:

1. A manifolding attachment for typewriters comprising a frame having members shaped to engage a part of the typewriter carriage and removably support said frame 100 thereon, said frame and said carriage having parts coöperating to secure said frame in operative position on said carriage, ribbon spools and guides mounted on said frame, and ribbon feeding devices mounted on said frame and comprising an actuating member adapted to be moved into and out of operative relation with a movable part of said typewriter when said frame is moved into 105 and out of its operative position on said carriage.

2. A manifolding attachment for typewriters comprising a frame having members shaped to pivotally engage a fixed part of the typewriter carriage to enable said 110 frame to be moved into and out of operative position, a fastening device to secure said frame in operative position, ribbon spools and guides mounted on said frame, and ribbon feeding devices mounted on said frame and comprising an actuating member adapted to be moved into and out of 115 operative relation with a movable part of said typewriter when said frame is moved about its pivotal support.

3. The combination, with a typewriter carriage, of a manifolding attachment comprising a frame having parts shaped to engage parts of said typewriter to support 120 said frame thereon, ribbon spools and 125

- guides carried by said frame and arranged to support a supplemental ribbon in operative position on said carriage when said frame has been placed in operative position 5 on said carriage.
4. A manifolding attachment for typewriters comprising a frame having slotted members to engage a part of the typewriter carriage and pivotally support said frame thereon, whereby said frame may be readily attached to and detached from said carriage and when attached to said carriage may be moved into and out of operative position, means to hold said frame against 10 pivotal movement, and ribbon spools and guides carried by said frame.
5. A manifolding attachment for typewriters comprising a frame having slotted members to engage a part of the typewriter carriage and pivotally support said frame thereon, whereby said frame may be readily attached to and detached from said carriage and when attached to said carriage may be moved into and out of operative 15 position, a clamping device to hold said frame against movement relatively to said carriage, and ribbon spools and guides carried by said frame.
6. The combination with a typewriter carriage having line spacing mechanism, of a manifolding attachment comprising a frame adapted to be pivotally mounted on said carriage, ribbon spools and ribbon guides mounted on said frame, and ribbon feeding 20 devices also mounted on said frame and adapted to be moved into and out of operative relation with said line spacing mechanism by the pivotal movement of said frame.
- 40 7. The combination with a typewriter carriage having line spacing mechanism, of a manifolding attachment comprising a frame having parts shaped to engage parts of said typewriter carriage to support said frame thereon, ribbon spools and guides carried by said frame, and a ribbon feeding device also carried by said frame and arranged to be moved into operative relation with said line spacing mechanism when 45 said frame is placed on said carriage with said ribbon in an operative position.
8. The combination, with a typewriter carriage having line spacing mechanism, of a manifolding attachment comprising a frame having parts shaped to engage parts of said typewriter carriage to pivotally support said frame thereon for movement into and out of operative position, ribbon spools and guides carried by said frame, and a 50 ribbon feeding device also carried by said frame and arranged to be moved into operative engagement with said line spacing mechanism when said frame is moved about its pivotal support on said carriage to place 55 said ribbon in an operative position.
9. The combination with a typewriter carriage comprising a rod extending lengthwise thereof, of a manifolding attachment comprising end plates slotted to engage said rod to pivotally support said frame thereon, 70 ribbon spools mounted on said frame, ribbon guides carried by said frame and adapted to be moved into and out of operative position as said frame is moved about its axis, and means to lock said frame against 75 movement about said axis.
10. The combination with a typewriter carriage comprising a rod having flat end portions, of a manifolding attachment having frame members provided with inclined 80 slots adapted to receive the flat portions of said rod, said slots having their inner ends enlarged to permit said frame to move about the axis of said rod, means to secure said frame against pivotal movement and retain 85 the same with said slots in inclined position relative to said rod, and ribbon spools and guides carried by said frame.
11. The combination with a typewriter carriage having line spacing mechanism, of a manifolding attachment comprising frame members slotted to engage parts of said carriage and pivotally support said frame thereon, a catch to hold said frame against pivotal movement, ribbon spools and guides 90 mounted on said frame, a ribbon feeding device mounted on said frame comprising a ratchet connected with one of said ribbon spools, a pawl to actuate said ratchet, a lever to operate said pawl, said lever having 95 a part extending into the path of a movable part of said line spacing mechanism, whereby the movement of said line spacing mechanism will operate said ribbon feeding mechanism. 100
12. The combination with a typewriter carriage having line spacing mechanism, of a manifolding attachment comprising frame members slotted to receive parts of said carriage and pivotally support said frame thereon, a catch to hold said frame against pivotal movement, a shaft journaled in said frame, ribbon spools loosely mounted on said shaft, means for clutching either of 110 said spools to said shaft to cause it to rotate therewith, and an actuating mechanism for imparting rotatory movement to said shaft, comprising a lever adapted to extend into the path of a movable part of said line spacing mechanism, and ribbon guides carried by said frame. 115
13. The combination with a typewriter carriage, having a platen journaled therein and line spacing mechanism to rotate said platen, of a manifolding attachment comprising a frame having members shaped to engage fixed parts of said carriage and pivotally support said frame thereon, a shaft journaled in said frame, ribbon spools loosely mounted on said shaft, clutch devices 120
- 130

to connect either of said spools with said shaft, ribbon guides carried by said frame and adapted to be moved into and out of positions adjacent to said platen, an actuating mechanism for said shaft comprising a lever carried by one of said frame members, said lever being so arranged that when said ribbon guides are in their positions adjacent to said platen said lever will extend into

the path of a movable part of said line 10 spacing mechanism.

In testimony whereof, we affix our signatures in presence of two witnesses.
